(57) **CLAIM**

I claim the ornamental design for a multi-dimensional antenna, as shown.

DESCRIPTION

FIG. 1 is a front perspective view of a multi-dimensional antenna depicting my new design.

FIG. 2 is a front view of the multi-dimensional antenna of FIG. 1.

FIG. 3 is a rear view of the multi-dimensional antenna of FIG. 1.

FIG. 4 is a left-side elevation view of the multi-dimensional antenna of FIG. 1.

FIG. 5 is a right-side elevation view of the multi-dimensional antenna of FIG. 1.

FIG. 6 is a top plan view of the multi-dimensional antenna of FIG. 1; and,

FIG. 7 is a bottom plan view of the multi-dimensional antenna of FIG. 1.
